PRESSURE LUBRICATING APPARATUS

Werner Max Josef Jüllig, Stockholm, Sweden,
assignor to Sven Magnus Zackarias Täcklind,
Stockholm, Sweden

Application March 10, 1931, Serial No. 521,566,
and in Germany September 13, 1930

9 Claims. (Cl. 184—36)

The present invention refers to a forced lubrication apparatus for oils, fats or similar lubricants, which may be utilized as well alone as also specially as low pressure part for a high pressure lubrication apparatus with as many lubricating means as desired which are arranged concentrically about the driving pump shaft. The invention brings about considerable improvements within that sphere of utilization in which the same is intended to be used. The forced lubrication apparatus works fully reliable and is able to overcome the frictional resistances in the suction conduit of the high pressure part and also in the sieve in front thereof, even if the fat is tough in itself or has become tough by the influence of cold. In this case the fat will be worked and kneaded in such a manner that air bubbles which possibly may be present in the lubricant, are practically entirely removed and thus the cylinders of the high pressure part can no longer wholly or partly be filled with air. With respect to its mechanical construction the invention is simply arranged and further is easily handled and works faultlessly even without careful supervision. Essentially for obtaining the above stated improvement is, according to the invention, the provision of a feeding member which has an inclined position, performs a circular swinging movement and has substantially the form of a disk. This feeding member performs a rolling movement upon the lubricant whereby the latter is displaced out of the container through discharge openings. Preferably this feeding member consists of a disc with a lower conical surface and an upper spherical surface, which disc is rotatable on an inclined spindle connected with a rotary drive shaft.

For the illustration of the invention one form of embodiment is shown on the drawing. Fig. 1 is a vertical section through a fat lubricating apparatus constituting the low pressure part for a high pressure lubrication apparatus, the feeding member being shown in elevation. Fig. 2 is a plan view of the apparatus, while Figs. 3—8 show constructional details and diagrams for the elucidation of the invention.

The frame 1 of the apparatus contains at its lower part one or more piston pumps, not shown, of conventional construction, of which only the suction channels 2 are shown. The vertical driving shaft 3, the upper part of which only has been shown, imparts to the pumps, for instance by means of gear wheels or worm wheels, their working movement, and this in such a manner that the separate pumps become active one after an-

other. The frame 1 forms with its upper part a container, at the bottom of which are cut out grooves 4, into which the suction channels 2 open. Above the grooves is placed an annular sieve 5 which is connected to and is pressed down by a bottom ring 6, the shape of which will later be described.

With the shaft 3 is releasably connected an inclined spindle 7 which for the sake of greater clearness is shown separately on a smaller scale in Fig. 3. On this inclined spindle is rotatably journalled a disk-like feeding member 8, that is to say a rolling disk with a lower conical surface and an upper spherical surface. The same is shown in section and on a smaller scale in Fig. 4. On the frame 1 are provided pins 9 and the rolling feeding member 8 carries corresponding pins 10 sunk down in a groove 11. These pins constitute in pairs a toothed gearing to impart to the feeding member 8 a rotary movement about its own axis.

To the inclined spindle 7 is securely fastened an arm 12 in the shape of a sickle. The inclined spindle 7 engages with its vertical lower spindle portion 14 a central bore hole in the shaft 3 and is carried along by means of a carrier pin 13 fixed to the spindle portion 14 and is prevented from being displaced upwards by a bayonet lock 33. The upper spindle portion 16 of the inclined spindle 7 supports one or more wipers 18 fixed to the same and bent in the form of an evolvent, which fits intimately to the outer surface of the feeding member 8. The connection between the spindle portion 16 of the inclined member and a wiper 18 is effected by means of a screw bolt 15. The mode of operation of the invention is the following.

If the container is filled with fat and the main shaft 3 is subjected to rotation in a clockwise direction, the said shaft carries along the inclined spindle 7 by means of the carrier pin 13 (Fig. 3), in which rotation also the sickle-like member 12 partakes. The feeding member 8 performs on one hand a circular swinging movement, that is to say, all points, for instance at its circumference, perform besides a circular movement simultaneously also a vertical reciprocating movement, and on the other hand a movement of its own about the spindle portion 16 in counter clock-wise direction, and this on account of the pairs of pins 9, 10 acting as a gearing. In the pitch circle of these pin pairs an exact rolling of the feeding member 8 takes place.

A shoulder 19 of the container and the upper surface of the ring 6 situated in the container,

are conically inclining towards the vertical axis of the container. As further the sickle-like member 12 at its front edge 20 is sharpened like a knife edge and bent in the shape of an evolvent and further bent up, seen in the direction of rotation, the same cuts off portions of the fat from below and transports the same through the crescent-shaped opening 21 to the space underneath the feeding member 8 and above the sieve 5.

At the rotation and rolling of the feeding member 10 and on account of the described movements of the parts the distance between the underneath side of the feeding member and the sieve 5 is gradually reduced to the size a shown in Fig. 1, and the fat is pressed through the sieve into the suction openings 2. This operation is considerably assisted by the fact that the feeding member 8 always on that side, at which displacing action or a super-pressure arises, grips under the bottom ring 6, so that the fat is prevented from escaping in an outward radial direction. Each wiper 18 scrapes the fat from the feeding member and assists in the complete emptying of the fat container.

In order to better elucidate the favorable action obtained by the gearing pins and the own motion of the feeding member caused by the same, the following is to be mentioned in referring to Figs. 5-7.

If one places a lump of fat 24 on the sieve 22 (Fig. 5) and will press the same by means of an inclined plate 25 which is moved in the direction of the arrow x , through the sieve, this will without difficulties be possible, provided the fat is soft. If however the fat is tough and at the same time possibly also cooled, an inconsiderable through-passage only of the fat through the sieve will take place, and the super-pressure obtained at the underneath side of the sieve 22 is low or practically equal to nought. The operations are not either otherwise if one utilizes stirring wings or conveying screws. If one places a pressure plate 28 in a horizontal position upon a lump of fat 27 and presses the plate down in the direction of the arrow y (Fig. 6), a comparatively large fat quantity passes through the sieve and on the underneath side of the sieve arises a considerable super-pressure. It will further be found that with the arrangement according to Fig. 5, the fat quantity pressed through the sieve will become the less the tougher the fat is, while with the arrangement according to Fig. 6, the transferred quantity becomes practically constant, when the fat becomes tougher, because at increasing consistence also the resistance of the fat against giving way in lateral direction increases. In this connection the extreme case which possibly may arise with an arrangement according to Fig. 5, shall be touched, that is to say, when the lubricant is stiff. In this case a displacement of the lubricant through the sieve will no longer take place and the body 24 will only glide along the upper surface of the sieve, excepting that case, where self-locking arises on account of too small an inclination of the plate 25 relatively to the sieve 22.

Similar conditions as with the arrangement according to Fig. 6 prevail also then, if according to Fig. 7 a cylindrical surface 30 having the greatest possible radius of curvature, rolls at a distance z over the sieve 29 and thereby acts upon a lump of fat 31. The excess of fat which is not passed through the sieve, will in this case be pushed in front of the rolling cylinder. The size of the distance z is also in this case of im-

portance for the displaced quantity, and this becomes the greater the less the distance z is. In practice a certain size for the distance z must not be surpassed, because space must be left between the rolling cylinder (the feeding member) and the sieve for hard bodies present in the lubricant, in order to avoid damage to the apparatus. The conditions with the arrangement according to Fig. 7 will still be more favorable, if simultaneously with the rolling movement of the cylinder in the direction of the arrow v also a smaller rotary motion about the geometrical axis of the cylinder takes place in the direction of the arrow u , inasmuch as in this case the body of fat 31 has less tendency to let itself be pushed in front of the cylinder 30, and instead thereof the same will on account of the action of adhesion be drawn more powerfully into the wedge-shaped space between the cylinder and the sieve.

A combination of all the above stated courses of events will be found in the mode of operation of the conical feeding member 8 according to the invention. In the pitch circle of the pins 10 a pure rolling is performed, while the part A of the rolling disk situated above the groove 4 performs relatively to the sieve a movement in a direction opposite to the direction of rotation of the apparatus.

In mounting the feeding member, the same is placed from below into the bottom ring 6, the vertical part 14 of the inclined member 7 is inserted in the bore hole of the driving shaft 3 and is turned thereafter so much, that the carrier pin 13 engages the bayonet aperture 33 (Fig. 8). The assembling and taking to pieces of the device thereby becomes extraordinarily simple. The sieve 5 is fixed to the bottom ring 6 from below and may thus together with the latter and with the feeding member 8 easily be taken out of the fat container of the apparatus by lifting said parts by means of the fixing screw bolt 15.

What I claim is:—

1. A forced lubrication apparatus comprising a container for the lubricant provided with discharge openings at the bottom of said container, a rotary drive shaft, an inclined spindle connected with said drive shaft, a rotary double disk journaled on said spindle and arranged to roll on the lubricant between said disk and said discharge openings, and cooperative engaging means on the container and double disk to force said double disk to rotate in a direction opposite to the rotation of said drive shaft.

2. A forced lubrication apparatus comprising a container for the lubricant provided with discharge openings at the bottom thereof, a rotary drive shaft, an inclined spindle connected to said drive shaft, a rolling feeding member journaled on said spindle and having a lower conical surface and an upper spherical surface, and a guide ring having a spherical surface in operative contact with the upper spherical surface on said feeding member, in such manner that an opening in the shape of a crescent is provided between the feeding member and the edge of the guide ring.

3. A forced lubrication apparatus comprising a container for the lubricant provided with discharge openings at the bottom thereof, a rotary drive shaft, an inclined spindle carried by said drive shaft, a feeding member journaled on said spindle and having a lower conical surface to roll on the lubricant between said disk and said discharge openings and an upper spherical surface, and spherical surface means within said contain- 150

- er and in operative contact with the upper spherical surface on said feeding member, in such manner that an opening in the shape of a crescent is provided between the feeding member and 5 said spherical surface means.
4. A forced lubrication apparatus comprising a container for the lubricant provided with discharge openings at the bottom thereof, a rotary drive shaft including an inclined spindle, a rotary feeding member journaled on said spindle, an annular feeding member in operative contact with said rotary feeding member in such manner as to provide a crescent shaped feeding opening, and a knife means attached to said first member 10 and extending through said feeding opening.
5. A forced lubrication apparatus comprising a container for the lubricant having discharge openings at the bottom thereof, a rotary drive shaft including an inclined spindle, a rotary feeding member journaled on said spindle, an annular member in operative contact with the rotary member so as to form a crescent shaped feeding opening, a knife means attached to said feeding member and extending through said feeding opening, and wiper means attached to said spindle and in operative contact with said feeding member.
6. In a lubricator of the type including a container for the lubricant having discharge openings at the bottom thereof, a rotary drive shaft and a feeding member, said drive shaft including an inclined spindle to rotatably support said feeding member, teeth means at the bottom of 35 said container, teeth means on the lower surface
- of said feeding member and in engagement with the teeth means at the bottom of said container, whereby the feeding member is adapted to perform a rolling movement.
7. In a lubricator of the type including a container for the lubricant, a rotary drive shaft and a feeding member, said drive shaft including an inclined spindle to rotatably support said feeding member, teeth means at the bottom of said container, and teeth means at the lower surface of said feeding member, in engagement with and arranged at a different pitch and in a different circumference from that of the teeth means at the bottom of said container.
8. In a lubricator of the type including a container for the lubricant, a rotary drive shaft and a feeding member, an inclined spindle to rotatably support said feeding member, a bayonet locking means to connect said drive shaft with said spindle, and means to force said feeding member to perform a rotary movement about its own axis.
9. In a lubricator of the type including a container for the lubricant having discharge openings at the bottom thereof, a rotary drive shaft 100 and a feeding member, an inclined spindle connected with said drive shaft and adapted to rotatably support said feeding member, sieve means on the top of said discharge openings, said feeding member provided with a lower conical surface, and said conical surface being adapted to roll on the lubricant at a minor distance above said sieve means.
